[57] CLAIM

The ornamental design for a shoe sole, as shown and described.

DESCRIPTION

FIG. 1 is a perspective view of a shoe sole showing our new design;

FIG. 2 is a left side elevational view thereof shown rotated approximately 180 degrees;

FIG. 3 is a front elevational view thereof shown rotated approximately 180 degrees;

FIG. 4 is a right side elevational view thereof, shown rotated approximately 180 degrees;

FIG. 5 is a rear elevational view of FIG. 3;

FIG. 6 is a top plan view of FIG. 3;

FIG. 7 is a bottom plan view of FIG. 3; and,

FIG. 8 is a left side elevational view of FIG. 2 shown rotated 90 degrees in a clockwise direction, the broken line showing the show upper being for illustrative purposes only and forms no part of the claimed design.
